COMBINED SPOON AND SPATULA

Lloyd S. Nicholson, 784 Locust St., Pasadena, Calif.

Filed Dec. 22, 1959, Ser. No. 58,769

Term of patent 7 years

(Cl. D44—29)

I claim:

The ornamental design for a combined spoon and spatula, as shown.
